UNITED STATES PATENT OFFICE

ALFRED W. F. GUEST, OF BROOKLYN, NEW YORK, ASSIGNOR TO MERGENTHALER LINOTYPE COMPANY, A CORPORATION OF NEW YORK.

LINE-CASTING MACHINE.

1,079,486.

Specification of Letters Patent.

Patented Nov. 25, 1913.

Application filed October 25, 1910. Serial No. 589,028.

To all whom it may concern:

Be it known that I, ALFRED W. F. GUEST, of the borough of Brooklyn, county of Kings, and State of New York, have invented a new and useful Improvement in Line-Casting Machines, of which the following is a specification.

My invention has reference to line casting machines of the Mergenthaler type, wherein 10 matrices released one at a time from a magazine descend through vertical guides to the surface of an inclined belt, whereby they are carried downward, and delivered successively into a channeled assembler, in which 15 they are assembled or composed side by side in a common line. In the modern machines of this character provision is made for speedy substitution of one font of matrices for another. Matrices of different fonts, 20 and sometimes matrices of the same font, differ widely in thickness and in weight; and it is found that the thick and heavy matrices are liable at times to descend with objectionable velocity and violence to their 25 position at the end of the line, the effect being to disturb the line, and also to injure the preceding matrix.

The object of my invention is to overcome this difficulty by the provision of a yielding 30 guide or resistant of such character that while all matrices are permitted to descend freely to the line, the thicker matrices are subjected, in advance of the line, to a retarding or resisting influence automatically 35 variable in proportion to the weight of the matrices. To this end I employ a yielding resistant overlying the path of the descending matrices in advance of the point at which the matrices are assembled. In its 40 preferred form this resistant consists of two or more superposed springs, fixed at their upper ends, and having their lower ends in position to contact with the matrices.

In the drawings I have shown my improvement applied to a commercial Mergenthaler linotype machine of the present day—which may be in all other respects of the ordinary construction.

In the drawings: Figure 1 is a front elevation of the composing mechanism having my improvement incorporated therein. Fig. 2 is a perspective view showing the resistant detached from the other parts. Fig. 3 is a cross-section on the line 3—3 of Fig. 1.

Referring to the drawings, A represents

the inclined magazine, from the lower end of which the designated matrices are delivered one at a time by the usual escapements and finger-key mechanism. B is the vertically channeled face-plate through which 60 these matrices descend by gravity.

C is the inclined, constantly rotating belt on which the matrices are received, and by which they are carried downward to the left, over the stationary support D, into position in front of the star wheel E, by which they are urged rearward and downward into the upper, channeled end of the assembler F. The matrices are thus delivered successively, 65 side by side, into the assembler, and are 70 ranged therein in a common line.

All the foregoing parts may be of the ordinary construction.

In carrying my invention into effect I provide a spring resistant, G, and fix the 75 same in position over the lower end of the assembler belt, or over the stationary surface on which the matrices travel. This resistant consists of a series of springs, g, g', etc., having their upper ends separated by 80 intermediate plates g⁵, and secured rigidly in position by screws g⁶, which pass through the springs and the plates into a stationary supporting bracket, g⁷. The lower ends of the springs, which are highly flexible, overlie the path of the matrices, each spring preferably extended downward beyond the one beneath it so as to terminate at different distances from the point of composition. Each spring terminates at a point 85 nearer the matrix-supporting surface than the one above. As a result of this arrangement the springs will act individually or cumulatively in resisting the passage of the matrices according to the thickness of the 90 latter.

Thin matrices descending toward the assembler will entirely escape the springs, or will be acted upon only by the innermost, or lowermost, spring. Matrices somewhat 105 thicker will lift the first spring, and will be acted upon thereby, and also by the second spring, while the thicker matrices will be acted upon by three springs—and so on successively—very heavy, thick, matrices meeting the resistance of all the springs. In this manner the rapidly moving matrices are subjected to resistance in proportion to their weight and momentum, and a sufficiently rapid rate of delivery to the assembler.

2
bler is secured, while at the same time the matrices are prevented from striking violently when arrested in the line.

Having described my invention, what I claim is:

1. In a mechanism of the class described, a matrix retarding device comprising a plurality of springs, fixed at one end, and having their free ends terminating at different distances from the point of composition so as to act individually or cumulatively in resisting the passage of the matrices, according to the thickness of the latter.
- 10 2. In a mechanism of the class described,

a matrix retarding device comprising a plurality of superposed springs overlying the matrix path, and adapted to act individually or cumulatively so as to offer varying resistance to the passing type or matrices in proportion to the thickness of the latter.

In testimony whereof I hereunto set my hand this twenty first day of October, 1910, in the presence of two attesting witnesses.

ALFRED W. F. GUEST.
